UNITED STATES PATENT OFFICE.

FREDERICK J. KALDENBERG, OF NEW YORK, N. Y.

DESIGN FOR AN UMBRELLA-HANDLE.

SPECIFICATION forming part of Design No. 11,733, dated April 13, 1880.

Application filed February 26, 1880. Term of patent 3½ years.

To all whom it may concern:

- Be it known that I, FREDERICK J. KALDENBERG, a citizen of the United States, residing at New York, in the county and State of New York, have invented and produced a new and original Design for Umbrella or Parasol Handles, of which the following is a specification, reference being had to the accompanying drawing, forming part thereof.
- 10 My invention has for its object the production of a novel and elaborate design for umbrella or parasol handles; and it consists in fashioning the handle to represent an arm and hand clad in ancient armor.
- 15 The accompanying drawing fully illustrates my newly-invented design.
- a* is the lower part of the handle, which may be plain or ornamented and of any form desired. From the point *a'* the handle takes the 20 general configuration of an arm and hand.
- b b* represent plate-armor, with which the arm is clothed; *c*, the coudière or elbow-guard, and *d* the gauntlet. The coudière may be more or less ornamented on its edges, as shown at 25 *e e*.
- f* represents a shield held and supported upon the fore-hand by the grasping-band *g*.
- The face of the shield may be unadorned or elaborately carved with appropriate symbolic figures or characters. Any one of the 30 parts of the mailed arm may be made of ma-

terial differing from the others, to afford greater elegance to the design.

The design, as a whole, may be greatly enriched by fluting or elaborate carvings without 35 altering the character of my invention, as

What I claim as new, and desire to secure by Letters Patent, is—

1. The design for an umbrella or parasol handle, consisting of the representation of an 40 arm and hand clad in armor, as described, and shown in the accompanying drawing.
2. The design for an umbrella or parasol handle, consisting of the representation of an arm clad in mail, with the coudière and gauntlet, substantially as described, and as described 45 and shown in the accompanying drawing.
3. The design for an umbrella or parasol handle, consisting of the representation of an arm and hand clad in armor, bearing a shield, 50 as described, and shown in the accompanying drawing.
4. The design for an umbrella or parasol handle, consisting of the representation of an armor-clad arm, with coudière, gauntlet, and 55 shield, as described, and shown in the accompanying drawing.

FREDERICK J. KALDENBERG.
